(57) **CLAIM**

The ornamental design for a vertical carrier, as shown and described.

DESCRIPTION

FIG. 1 is as the view of the vertical carrier in FIG. 1 with a front panel shown in solid lines;

FIG. 2 is a rear-elevation view of the carrier shown in FIG. 1;

FIG. 3 is a front-elevation of the carrier shown in FIG. 1; FIG. 4 is a side-elevation view from left of the carrier shown in FIG. 1;

FIG. 5 is a side-elevation view from right of the carrier shown in FIG. 1;

FIG. 6 is a plan view from above the carrier shown in FIG. 1;

FIG. 7 is a plan view from below the carrier shown in FIG. 1;

FIG. 8 is a perspective view from above the vertical carrier shown in FIG. 1, with a pattern of holes defined by the front panel shown in solid lines;

FIG. 9 is a rear-elevation view of the carrier shown in FIG. 8;

FIG. 10 is a front-elevation of the carrier shown in FIG. 8; FIG. 11 is a side-elevation view from left of the carrier shown in FIG. 8;

FIG. 12 is a side-elevation view from right of the carrier shown in FIG. 8;

FIG. 13 is a plan view from above the carrier shown in FIG. 8; and,

FIG. 14 is a plan view from below the carrier shown in FIG. 8.

In the drawings, the broken lines depict portions of a vertical carrier that form no part of the claimed design.

1 Claim, 14 Drawing Sheets
